DEVICE FOR HOLDING DECANTERS OR SIMILAR ARTICLES

James E. Faulkner, Tuckahoe, N. Y., assignor to Lador, Incorporated, New York, N. Y., a corporation of New York

Application January 19, 1956, Serial No. 39,851

Term of patent 7 years

(Cl. D44—21)

Fig. 1 is a front elevation view of a device for holding decanters or similar articles;

Fig. 2 is a side elevation of the new design; and

Fig. 3 is a top view thereof.

The dominant features of my design reside in the portions disclosed in full lines in the drawing.

I claim:

The ornamental design for a device for holding decanters or similar articles, substantially as shown and described.
